CLAIM

The ornamental design for a flat bag encapsulation apparatus, as shown.

DESCRIPTION

FIG. 1 is a front elevational view of the flat bag encapsulation apparatus of the present invention;

FIG. 2 is a back elevational view of the flat bag encapsulation apparatus of FIG. 1;

FIG. 3 is a left side elevational view of the flat bag encapsulation apparatus of FIG. 1;

FIG. 4 is a right side elevational view of the flat bag encapsulation apparatus of FIG. 1;

FIG. 5 is a top plan view of the flat bag encapsulation apparatus of FIG. 1; and,

FIG. 6 is a bottom plan view of the flat bag encapsulation apparatus of FIG. 1.
